FOREIGN PATENT DOCUMENTS1313296 11/1962 France ..... 43/43.13 |*Primary Examiner*—Doris V. Coles*Attorney, Agent, or Firm*—Kolisch, Hartwell, Dickinson, McCormack & Heuser**[57] CLAIM**

The ornamental design for a fishing lure, as shown and described.

DESCRIPTION

FIG. 1 is a top plan view of a fishing lure showing my new design;

FIG. 2 is a bottom plan view thereof;

FIG. 3 is a rear elevation view thereof;

FIG. 4 is a front elevation view thereof;

FIG. 5 is a side elevation view thereof;

FIG. 6 is a top plan view of a fishing lure showing an alternate embodiment of my new design;

FIG. 7 is a bottom plan view thereof, with a sprue portion shown in dashed lines. The sprue portion forms no part of the claimed invention;

FIG. 8 is a rear elevation view thereof, with one end of a passage shown in dashed lines. The passage forms no part of the claimed invention;

FIG. 9 is a front elevation view thereof, with another end of the passage shown in dashed lines; and,

FIG. 10 is a side elevation view thereof, with the sprue portion shown in dashed lines.
